UNITED STATES PATENT OFFICE.

MYRON J. AMICK AND JOHANNES ROOS, OF NEW YORK, N. Y.

SAFETY-FENDER.

SPECIFICATION forming part of Letters Patent No. 535,184, dated March 5, 1895.

Application filed February 16, 1894. Serial No. 500,399. (No model.)

To all whom it may concern:

Be it known that we, MYRON J. AMICK, a citizen of the United States, and JOHANNES ROOS, a subject of the German Emperor, both 5 residents of New York, in the county of New York and State of New York, have invented certain new and useful Improvements in Safety-Fenders, of which the following is a specification.

10 Our invention relates to safety fenders for cars, and consists of a combination of devices by means of which the front edge of a scoop forming a part of the fender, is dropped automatically to the pavement in front of the 15 car wheels by a good sized obstruction, which is thereafter picked up by, and carried in the scoop, until the car is stopped, thus preventing accidents.

In the accompanying drawings, Figure 1 is 20 a longitudinal section of the lower end of a street car, showing the device attached to it in two positions. Fig. 2, is a bottom view of Fig. 1.

Upon a shaft *a* secured transversely under 25 the bottom of a car, in front of the wheels by the brackets *a'*, is rotatably mounted one end of the frame *b* of a scoop *B*, the covering of which consists preferably of close network *b'* while the front edge *b''* is preferably selected 30 from an elastic material of a certain degree of stability, such as heavy strips of vulcanized rubber, and the like. Closely behind this strip and under the netting, are mounted, preferably on a shaft secured in the frame 35 *b*, two rollers *b''*, which will touch the rails when the front end of the scoop is dropped (in a manner hereinafter described) and guide the front edge of the scoop in close proximity of, and almost touching the road-bed between 40 the two rails, so that any object lying upon the road is caught and carried upon the network of the scoop *B*.

The scoop *B*, is made preferably of the shape indicated in the drawings, and the 45 front part of it is ordinarily held in an approximately horizontal position as shown in Fig. 1 of the drawings by means of two straps *s*, secured to the frame and passing from there upward over two rollers *c c*, secured 50 closely under the bottom of the car, and from there to and partially around the drums *d d* secured upon a shaft *e*, rotatably mounted in

bearings *e'* secured under the front platform of the car, their ends being secured to the peripheries of said drums. To the shaft *e* are 55 also secured two sprocket wheels, one *f* near the center of the shaft *e*, and the other *f'* near one end of the shaft *e* which is provided at one or both ends with square heads for the attachment of a portable crank. 60

Upon a shaft *g* bent at one end and rotatably mounted in bearings *g'* secured under the bottom of the front platform is secured the pawl *p*, one end of which engages with the teeth of the sprocket-wheel *f*, and will 65 prevent it from turning when the opposite end of the pawl *p* is supported by a segmental disk *h'* forming part of the frame of a trap-door or flap *h*, hung in front of the car under the front platform and oscillating upon a 70 shaft *i* secured parallel to a wheel axle at the bottom of the front platform. This flap *h* is made very light, the spaces in its frame being preferably filled with wire-netting, and it extends across the entire width of a car, being 75 suspended preferably in an inclined position from the shaft *i* with its padded lower edge adjusted at a distance from the road bed and from a vertical plane through the shaft *i* sufficient to allow smaller obstacles to pass, but 80 not far enough to let a larger object pass without touching it. These objects will throw it back sufficiently to trip the pawl *p* and thus relieve the tension upon the straps *s*, allowing the outer edge of the scoop *B*, to fall 85 to the ground in time to catch the object and prevent its being ground by the wheels. A pawl *k* secured preferably on a bracket *a'* engaging with a notch in the frame *b* of the scoop, will prevent the latter from leaving 90 the ground when once dropped, till the car has been stopped, insuring the safe scooping of any object in front of the car. Another pawl *o* secured upon the car frame in a position to engage the sprocket-wheel *f'* will, 95 when thrown in, hold the scoop *B* in the desired position, till the pawl *p* is thrown in position and the segment *h'* slipped under its other end when the pawl *o* will be thrown back to a position shown in Fig. 1 of the 100 drawings, leaving the scoop free to drop when the automatic trap is released.

The operation in setting the scoop is then as follows: The pawl *k* being thrown out of

contact with the frame *b*, and the pawl *o* into contact with the sprocket-wheel *f'*, a portable crank is placed upon the square end of the shaft *e*, and the shaft *e* is revolved in the direction indicated by the arrows in Fig. 1 of the drawings, and the motion is continued till the scoop is raised to a horizontal position as shown in full lines in Fig. 1. The pawl *p*, which arrived at a position shown in dotted lines in Fig. 1, after springing of the trap, is now thrown in contact with the wheel *f* by pushing the trap door *h* backward and turning the shaft *g*, and is then secured by allowing the flap *h* to drop in position, the segment *h'* slipping under the opposite end of the pawl *p* and locking it, thus preventing the shaft *e* from turning and supporting the scoop in its raised position by means of the straps *s*. The pawl *o* is then thrown back and the trap is thus free to drop the front end of the scoop *B*, whenever the flap *h* is swung backward by an object lying in the road and having the regulation size for which the apparatus is designed. It is apparent that, thus small obstacles are permitted to pass under the car without disturbing the trap which works the scoop, nor the scoop itself, and it

will require larger objects, such as the body of a child, to spring the trap and drop the scoop.

30

The dropping motion of the scoop may be accelerated by a spring or springs as indicated in Fig. 1 of the drawings.

In Fig. 1 of the drawings the working position of the scoop, after being tripped, is shown in dotted lines, and the position on the car while on the road, in full lines.

35

Having thus described our invention, what we claim, and desire to secure by Letters Patent, is—

40

In a safety fender, the combination of an oscillating flap *h* with a shaft *g* carrying a pawl *p*, a shaft *e*, carrying drums and sprocket wheels, a pawl *o*, straps *s*, rollers *c* and a scoop *B*, as and for the purposes herein shown and described.

45

Signed at New York, in the county of New York and State of New York, this 15th day of February, A. D. 1894.

MYRON J. AMICK.
JOHANNES ROOS.
